Attorney.

UNITED STATES PATENT OFFICE.

SANFORD R. HASKELL, OF ALBANY, NEW YORK.

UMBRELLA-HOLDER.

SPECIFICATION forming part of Letters Patent No. 411,521, dated September 24, 1889.

Application filed January 7, 1885. Serial No. 152,187. (No model.)

To all whom it may concern:

Be it known that I, SANFORD R. HASKELL, of the city and county of Albany, in the State of New York, have invented certain new and 5 useful Improvements in Umbrella-Holders, of which the following is a specification.

My invention relates to improvements in devices for holding umbrellas, &c.; and the object of my improvements is to provide a 10 device for the purpose named, which, (device,) when not in use for holding wet umbrellas, may be turned aside, so that it will occupy only a trifling space in the apartment where it is placed. This object I attain by means 15 of the mechanism illustrated in the accompanying drawings, which form part of this specification, and in which—

Figure 1 is a perspective view of my device attached to a wall and with the several 20 parts in position for use; Fig. 2, a vertical section of the same; Fig. 3, a horizontal section of the detachable drip-cup, and Figs. 4 and 5 enlarged and detached detail views of the hinge-joint for the swinging bracket.

As represented in the drawings, A is a 25 swinging bracket, made of metal and provided with any required number of circular openings for containing umbrellas. Said openings I preferably form of conjoining rings a, of sufficient size for containing one 30 or more umbrellas. The said rings are attached to a rearwardly-extending stem a', provided at each side with lateral pintles a² and a³.

B is a hinge-piece adapted to be secured 35 against a wall, door, or other vertical part of a room. Said hinge-piece is provided at its lower end with inwardly-projecting flanges of uniform thickness, formed of reversed 40 curves to produce the convex projecting portions b and b' and the intermediate concave portion b². Between the inner edges of said flanges there is an opening b³, through which the stem a' of the swinging bracket A passes, 45 so that the pintles a² will bear against the outer faces and the pintles a³ will bear against the inner faces of the flanges of the hinge-piece B.

When the hinge-piece B is secured in place, 50 as shown in Fig. 1, and the swinging bracket A is projected to receive umbrellas, &c., the

pintles a³ will rest against the under side of the flanges at the portion marked b, and the pintles a² will lie in the concave portion b² of said flanges, and the swinging bracket A will 55 thus be sustained in its extended position. To drop the swinging bracket A into the hanging position shown by the dotted lines in Fig. 2, the outer end of said bracket must first be swung upward, using the pintle a² as 60 a pivotal center, so as to carry the pintle a³ against the under side of the flange at the portion b', and then, by using the pintle a³ as a pivotal center, the outer end of the swinging bracket may be swung downward 65 to bring the pintle a² to the under side of the hinge-piece B, as shown by the dotted lines, exhibiting the pendent position of the bracket in Fig. 5.

The detachable drip-cup C is provided with 70 a dovetailed tenon c, that is adapted to engage in a counterpart dovetail piece D, which is designed to be secured to a wall or other similar vertical part of the room, underneath the swinging bracket A, so that the said drip-cup will serve as a receptacle for catching 75 the drainage from wet umbrellas.

When not required for use, the swinging bracket A may be turned down into its pendent position, and the drip-cup C may be removed from the dovetail piece D and put out 80 of the way.

I do not confine myself to the exact fastening herein shown and described for attaching the drip-cup C in a fixed position 85 beneath the swinging bracket A, as many different fastenings that differ only in a slight degree may be adopted for effecting the same purpose.

I claim as my invention—
90
In an umbrella-holder, the combination, with a swinging bracket A, provided with the lateral pintles a² and a³, as herein described, of the hinge-piece B, provided with inwardly-projecting flanges formed of the reversed curves b, b', and b², as and for the purpose herein specified.

SANFORD R. HASKELL.
